UNITED STATES PATENT OFFICE.

CLARENCE L. STEIN, OF AURORA, ILLINOIS, ASSIGNOR OF ONE-HALF TO HALSEY M. JOHNSON, OF AURORA, ILLINOIS.

FISH-STRINGER.

1,350,390.

Specification of Letters Patent. Patented Aug. 24, 1920.

Application filed October 6, 1919. Serial No. 328,938.

To all whom it may concern:

Be it known that I, CLARENCE L. STEIN, a citizen of the United States, residing at Aurora, in the county of Kane and State of Illinois, have invented a new and useful Fish-Stringer, of which the following is a specification.

This invention relates to means for use in stringing fish, one of its objects being to provide a simple and efficient device which can be attached to the belt of the user, or to any other suitable support and which, when in position, can be employed to string fish, it being possible, by the aid of said device, to remove the hooks from the fish and place the fish on the stringer by the use of one hand only, the other hand being employed for holding the pole.

A further object is to provide a device of this character which can be placed in position readily and which, after the fish have been strung thereon, can be used as a carrier and easily conveyed from place to place.

With the foregoing and other objects in view, which will appear as the description proceeds, the invention consists of certain novel details of construction and combinations of parts which will be hereinafter more fully described and pointed out in the claims, it being understood that various changes may be made in the construction and arrangement of the parts without departing from the spirit or sacrificing any of the advantages of the invention as set forth in the appended claims.

In the accompanying drawings the preferred form of the invention has been shown.

In said drawings

Figure 1 is an elevation of the device showing the position of the parts during the stringing operation, the position of said parts during the impaling of a fish prior to the stringing and during the removal of the hook, being indicated by dotted lines.

Fig. 2 is an elevation, on a reduced scale of the device showing the parts arranged for use as a carrier, the holding tube being inverted.

Referring to the figures by characters of reference, 1 designates a holding tube having its open upper end beveled and provided with a hook or clip 2 adapted to be placed

in engagement with a belt B or other supporting structure. An eye 4 is connected to the other end of the tube and is engaged by one end of a chain 5 or other flexible element, there being, preferably, a snap hook 6 for detachably securing the chain to the eye. The other end of the element 5 is connected preferably by a snap hook 7, to the intermediate portion of a stem 8 one end portion of which is adapted to be inserted downwardly into the tubular holder 1 while the remaining portion is extended at an angle to the holder engaging portion and is provided with a reduced end or threading head 9.

In using the device the holder 1 is attached to the belt of the user or to any other suitable support. One end of the stem 8 is inserted into the holder so that the other end portion will extend upwardly and outwardly therefrom, as shown. This will, obviously, form a closed loop. When a fish is caught the pole is held in the left hand while with the right hand the fish is impaled on the upper end of the stem. The same hand is then used for removing the hook after which the stem 8 is lifted from the holder 1 and held with its lower portion parallel with the adjoining portion of the element 5. Thus the fish will slide onto said element 5 as indicated in full lines in Fig. 1. The stem is then again inserted in the holder 1, whereupon the operation described can be repeated. After the fishing has been completed, the stem is removed from the holder and the snap hook 7 is placed in engagement with the eye 4. Thus the element 5 with the fish thereon, forms a closed loop and the stem 8 can be used as a handle for carrying the device.

What is claimed is:—

1. A fish stringer including a holder, means for connecting the same to a support, a threading stem having one end insertible into the holder and the other end extending at an angle thereto, a flexible element detachably connected at one end to an intermediate portion of the stem and connected at its other end to the holder.

2. A fish stringer including a holder, means for attaching the same to a support, a threading stem having one end insertible into the holder to support the other end in

position beyond the upper end of the holder, a flexible element connected at one end to the holder and means at the other end of said element for connecting it to an intermediate portion of the stem, said last named connecting means constituting means for detachably engaging the holder.

In testimony that I claim the foregoing as my own, I have hereto affixed my signature in the presence of two witnesses.

CLARENCE L. STEIN.
